UNITED STATES PATENT OFFICE.

MAX C. MILLER, OF CUMBERLAND HILL, RHODE ISLAND, ASSIGNOR TO JENCKES
KNITTING MACHINE COMPANY, OF PAWTUCKET, RHODE ISLAND, A CORPORATION
OF RHODE ISLAND.

PATTERN MECHANISM FOR KNITTING MACHINES.

Original application filed April 5, 1921, Serial No. 458,640. Divided and this application filed May 27, 1922. Serial No. 564,209.

To all whom it may concern:

Be it known that I, MAX C. MILLER, a citizen of Germany, residing at Cumberland Hill, in the county of Cumberland and State of Rhode Island, have invented 5 certain new and useful Improvements in Pattern Mechanism for Knitting Machines; and I do hereby declare the following to be a full, clear, and exact description of the invention, such as will enable others skilled 10 in the art to which it appertains to make and use the same.

The invention relates to pattern mechanism for circular knitting machines.

15 The operation of the various parts of circular knitting machines such as are used for knitting seamless hosiery is usually controlled by a pattern mechanism which controls or dictates the throwing into and out 20 of operation of various needle operating devices, the operation of the yarn carriers in changing and feeding the yarns, and the changes in the motion of the rotary needle or cam cylinder.

25 It is the object of the present invention to provide a simple and efficient construction of pattern mechanism for this type of machine which not only insures the uniform and proper control of parts but also permits 30 a compact arrangement of the controlling cams about the drum or shaft on which they are mounted with a corresponding reduction in the size of the drum and in the idle movements imparted thereto. It is a further object of the invention to provide for 35 the ready removal and replacement of cams which usually require replacement or refitting in setting up the machine for certain classes of work or for changing it for different kinds of work.

40 To these ends the invention comprises the features of construction and combination of parts hereinafter described and set forth in the claims.

45 A preferred form of the invention is shown in the accompanying drawings embodied in a circular knitting machine which is fully shown and described in application Serial No. 458,640, filed April 5, 1921, 50 of which the present application is a division.

In the drawings Fig. 1 is a side elevation showing so much of the knitting ma-

chine as is necessary to illustrate the application of the present invention thereto, 55 Fig. 2 is an elevation looking toward the right in Fig. 1, Fig. 3 is a central section through the pattern cam shaft and Fig. 4 is a transverse section through the pattern cam shaft.

60 In the drawings the needle cylinder which forms the rotary element of the knitting head is indicated diagrammatically at 2. The cylinder is rotated and reciprocated through motion changing mechanism 65 which may be constructed as shown in the above application or may be of any well known construction. This mechanism includes a rotary pinion 4 and a similar oscillating pinion arranged in axial alignment therewith. The pinion 4 engages a gear 6 provided with a crank 8 connected by link 10 with the segment 12 which engages and oscillates the oscillating pinion. The needle cylinder is driven from one or the other 70 of the pinions through a beveled gear 14 engaging a similar gear 16 on the lower end of a shaft 18, the upper end of which carries a gear 20 engaging a gear 22 connected with the lower end of the needle cylinder. A clutch (not shown) operated by the pattern mechanism connects one or the 75 other of the pinions with the gear 14 to rotate or oscillate the needle cylinder.

80 The cams and devices for controlling and dictating changes during the operation of the machine are carried on a pattern shaft 24 which is intermittently advanced at intervals during the knitting through a ratchet wheel 59 secured to the end of the shaft. 85 The ratchet wheel is provided with teeth which are engaged at intervals by an actuating pawl 61 mounted on a pawl-carrying lever 62 and forced in a direction to engage the ratchet by a spring 63. The 90 pawl is normally held out of action by a latch 64 pivoted on the pawl-carrying lever and arranged to hook over a lug 65 on the side of the pawl. The latch is disengaged to render the pawl active at suitable intervals by a lever 66 one end of which is arranged to overlie the tail of the latch and the other end of which is arranged in the path of a series of lugs 67 on a pattern chain 68. A spring 69 connects the 95 latch and its controlling lever, and tends 100 105

to hold the latch in engagement with the lug 65 and to hold the lever in normal position with an arm 70 on the lever in engagement with a fixed stop 71.

5 The teeth on the ratchet 59 are of different lengths and the engagement of the actuating pawl with the proper tooth when the pawl is rendered active is insured by a guard 72, the position of which is automatically shifted to prevent engagement of the pawl with any but the proper tooth.

10 The guard is formed on the end of a lever which is pivoted at 73, and the position of the guard is controlled and determined by

15 a cam 74 secured to the inner side of the ratchet wheel and engaged by a bearing piece 75 which is adjustably secured on the end of the guard lever. The lever is held in engagement with the cam by a spring 75'

20 and the cam is so shaped that at each forward movement of the ratchet wheel the guard is properly positioned to insure the engagement of the pawl with the succeeding tooth when the pawl is next rendered

25 active. In order to insure the proper timed relation between the pattern chain and pattern shaft and to automatically restore the timed relation in case it is unintentionally disturbed, as in hand manipulation of the

30 machine, the cam 74 is provided at one point with an abnormally low part, as at 76, which will so position the guard that engagement of the pawl with the tooth of the ratchet wheel next to be engaged will

35 be prevented unless the guard is otherwise positioned to permit engagement of the tooth by the pawl. The guard is thus positioned by a timing or re-timing mechanism, comprising a lever 77, the upper end

40 of which is arranged to engage a pin 78 projecting from the guard lever, and the lower end of which is arranged at one side of the lower end of the pawl releasing lever 66 and in the path of a single broad lug 67'

45 on the pattern chain. If the chain and shaft are in proper time, the low point 76 on the cam 74 is brought into register with the contact piece on the guard lever by the engagement of the actuating pawl with the

50 tooth corresponding to the lug 67' next preceding the broad lug 67' on the pattern chain. When the pawl is to engage the next tooth the broad lug releases the pawl and at the same time the broad lug actuates the lever 77 to so position the guard 72 that

55 the pawl will engage the tooth and advance the pattern cam. If for any reason the shaft and chain are out of time the shaft will be advanced step by step by the pawl as it is released by the successive lugs 67 until the low point 76 on the cam 74 registers with the contact piece on the guard lever, after which there will be no advance of the shaft by the pawl when released until

60 the broad lug 67' is brought into active

position and not only releases the pawl but also moves the guard into position to permit the pawl to engage the tooth of the ratchet wheel corresponding to the lug 67' on the pattern chain.

70 The pawl-carrying lever 62 is actuated from a continuously rotating cam 79 secured to the end of a shaft 80, which is connected with the crank gear 6 for actuating the oscillating segment of the mechanism 75 for reciprocating the needle cylinder. The cam, therefore, makes one revolution and actuates the pawl during each complete oscillation of the segment or reciprocation of the needle cylinder during reciprocatory knitting, and during each four revolutions of the cylinder during rotary knitting. The cam is engaged by a cam lever 81 which is connected by a link 82 with the pawl-carrying lever. A spring 83 connected with the pawl-carrying lever tends to retract the pawl and holds the cam lever in engagement with the cam. Each time the pawl is retracted the end of the pawl rides against a fixed stud 84 arranged to swing the pawl 85 about its pivot and maintain it in position for the re-engagement of the latch 64 with the lug 65.

90 Since the various changes controlled or dictated by the pattern mechanism should occur at varying points in the revolution or reciprocation of the needle cylinder the pawl-actuating cam 79 is preferably provided with a plurality of rises or steps properly distributed along the periphery of the cam to give to the pawl a series of short and rapid advance movements timed with relation to the movements of the needle cylinder to coincide with the points at which the changes dictated by the pattern mechanism should be effected. This multiple step advance movement of the pawl not only enables the changes to be accurately timed without the necessity of extreme accuracy in the positioning of the controlling cams but also enables the cams to be more compactly arranged about the periphery of a drum on which they are mounted so that the diameter of the drum may be materially reduced. This feature, in connection with the variation in the lengths of the teeth of the ratchet wheel engaged by the pawl, enables the movements imparted to the pattern drum to be so selectively controlled as to reduce the idle movement of the drum and consequently enables the diameter of the drum to be further reduced.

100 105 110 115 120 125 130

In making certain changes as, for instance, in changing the yarns it may be desirable, under varying conditions, to vary the interval between two successive advance steps of the pattern drum pawl and means is therefore provided for varying the relative positions of successive rises on the cam 79. In the construction shown the pattern drum

is advanced by the step on the cam indicated at 84 to insert a new yarn and after a short interval is again advanced by the step 85 to withdraw an active yarn. In order that the lap of the yarns may be varied the rise 84 is formed by a plate adjustably secured to the main cam 79 and movable thereon to vary the position of the rise 84 with relation to the rise 85.

10 The pattern chain is advanced a step, for each revolution of the shaft 80, and therefore a step for each four revolutions of the needle cylinder, by a cam 86 secured to the shaft 80 and engaging a pawl-carrying lever 87. A pawl 88 is pivoted on the lever and is held by a spring 89 in engagement with the teeth of a ratchet wheel 90 which is secured to the upper pattern chain sprocket wheel 91. A stop pawl 92 prevents reverse movement of the ratchet wheel.

To enable the cams of the pattern mechanism to be accurately and conveniently positioned with relation to each other and with relation to the actuating mechanism, and also to enable certain of the cams to be readily replaced in adapting the machine for different kinds of work the cams carried by the pattern drum are made in the form of disks definitely located thereon and with relation to each other by a key and keyway or by other means which determines the circumferential position of each disk on the drum. The cams which usually require adjustment or refitting in setting up a machine for a certain kind of work or in changing from one kind to another are preferably in the form of thin metal disks which may be stamped from sheet metal and to enable each disk to be readily removed or replaced by one having a different contour the disks are split or made in two half-sections.

As shown in Fig. 3 the pattern drum 93 is secured to the shaft 24 by a pin 94 and is provided with a keyway 95 for circumferentially positioning the cam disks, and with a flange 96 against which the assembled cam disks are held by a nut 97. The two cam disks 98 which may carry the cams for controlling the motion changing clutch are comparatively thick one-piece disks, the outer one of which is recessed to receive the flange 96. The cam disk 98' at the other end of the drum, which may be provided with the cams for controlling the pickers, is also a comparatively thick one-piece disk. The intermediate cam disks 99 which may include the cams for actuating the yarn changers to insert and withdraw the various yarns, the cam for controlling the loosening of the stitch during the knitting in of a splicing yarn, and the cam for controlling the leveling of the needles when knitting half hose consist of thin metal disks which are split or formed in two half sections as indicated in Fig. 4 so that any disk may be removed and

replaced without removing the others and without disturbing the pattern drum or its shaft. The disks are provided with keys fitting within the keyway 95 to accurately position the disks circumferentially on the drum and they are spaced from each other by spacer disks 100. The assembled disks are bound together and held in axial position on the drum by the nut 97 and flange 96, between which they are clamped by tightening the nut. Overrunning of the cam shaft under the influence of its actuating pawl may be prevented by a friction spring 101 which is forced against a friction washer 102 within the end of the drum by a washer 103 and nut 104. The spring and washer 103 are held against rotation by a fixed pin 105.

While it is preferred to employ the specific construction shown and described in embodying the invention in the machine of the application above referred to it will be understood that this construction and arrangement is not essential to the broader features of the invention but may be varied or modified as found desirable or best suited to the construction and mode of operation of the machine in which it is to be embodied.

What is claimed is:

1. A knitting machine having, in combination, a pattern mechanism comprising a ratchet wheel having teeth of different lengths, an actuating pawl, a guard for determining the tooth engaged by the pawl when permitted to engage the ratchet, separate means for normally holding the pawl out of engagement with the ratchet, and means moving with the ratchet wheel for controlling the position of the guard.

2. A knitting machine having, in combination, a pattern mechanism comprising a ratchet wheel, an actuating pawl, a guard for determining the tooth engaged by the pawl when thrown into action, separate means for normally holding the pawl out of action, and means moving with the ratchet wheel for controlling the guard.

3. A knitting machine having, in combination, a pattern mechanism comprising a ratchet wheel having teeth of different lengths, a reciprocating actuating pawl normally held out of action, a guard for controlling the engagement of the pawl with the ratchet teeth after it is thrown into action, and a cam connected with the ratchet wheel for varying the position of the guard.

4. A knitting machine having, in combination, a pattern mechanism comprising a ratchet wheel, an actuating pawl normally held out of action, a guard for controlling the engagement of the pawl with the ratchet teeth after it is thrown into action, and a cam moving with the ratchet wheel for positioning the guard during each step of the ratchet wheel to secure the engagement of

the pawl with a predetermined tooth upon its next engagement with the ratchet wheel.

5. A knitting machine having, in combination, a pattern mechanism comprising a ratchet wheel, a reciprocating actuating pawl, and means moving with the ratchet wheel for varying the point in the reciprocation of the pawl at which it engages a tooth of the wheel in accordance with the 10 length of movement to be imparted to the wheel.

6. A knitting machine having, in combination, a pattern mechanism comprising a ratchet wheel, a normally inactive actuating pawl, means for intermittently causing the pawl to act on the ratchet wheel, and means moving with the ratchet wheel for varying the point in the reciprocation of the pawl at which it engages a tooth of the wheel in accordance with the 20 length of movement to be imparted to the wheel.

7. A knitting machine having, in combination, a pattern mechanism comprising a ratchet wheel, an actuating pawl, a latch for holding the pawl out of action, a pattern chain having a series of lugs for tripping the latch, a guard for controlling the engagement of the pawl with the teeth of the ratchet wheel, and means moving with the 30 ratchet wheel for controlling the guard.

8. A knitting machine having, in combination, a pattern mechanism comprising a ratchet wheel having teeth of different lengths, a reciprocating actuating pawl having a stroke greater than the longest tooth, means for normally holding the pawl out of engagement with the ratchet, a pattern mechanism for freeing the pawl, a guard for determining the tooth engaged by the pawl 40 when free, and means moving with the ratchet wheel for controlling the position of the guard.

9. A knitting machine having, in combination, a pattern mechanism comprising a ratchet wheel, a reciprocating actuating pawl, a latch for normally holding the pawl out of engagement with the ratchet wheel, a guard for determining the tooth engaged by the pawl when released by the latch, 50 means for positioning the guard for each active stroke of the pawl, and a pattern mechanism for operating the latch.

10. A knitting machine having, in combination, a main pattern mechanism comprising a ratchet wheel, a normally inactive actuating pawl, a guard for controlling the engagement of the pawl with the teeth of the ratchet wheel after the pawl has been thrown into action, supplemental pattern 55 mechanism for throwing the pawl into action to time the advance movements of the main pattern mechanism, means for positioning the guard to permit the pawl to engage the next tooth of the ratchet wheel only.

when the two pattern mechanisms are in 65 proper timed relation.

11. A knitting machine having, in combination, a main pattern mechanism comprising a ratchet wheel, a normally inactive actuating pawl, a guard for controlling the 70 engagement of the pawl with the teeth of the ratchet wheel after the pawl has been thrown into action, means moving with the ratchet wheel for determining the position of the guard constructed to prevent engagement of the pawl with the ratchet teeth in a 75 given position of the wheel, a supplemental pattern mechanism for intermittently rendering the pawl active to time the advance movement of the main pattern mechanism, 80 and means operated by the supplemental pattern mechanism when in proper timed relation with the main pattern mechanism to position the guard to permit engagement of the pawl with the next tooth.

12. A knitting machine having, in combination, a rotary knitting element, mechanism for rotating and oscillating said element, a pattern mechanism comprising a ratchet wheel, an actuating pawl, a cam 90 moving in time with the rotary element and having a plurality of rises to give the pawl a series of short rapid advance movements at points in the travel of the rotary element at which changes are dictated by the pattern mechanism, and means for adjustably varying the relative positions of successive rises.

13. A pattern mechanism for dictating changes in the parts of a knitting machine 100 comprising a drum, a series of cam disks thereon each consisting of sections adapted to be fitted together about the drum, means for determining the circumferential position of each disk on the drum, separating disks 105 between the cam disks, and means for binding the disks together and holding them in axial position on the drum.

14. A pattern mechanism for dictating changes in the parts of a knitting machine 110 comprising a drum, a series of cam disks each consisting of two half sections adapted to be fitted together about the drum, means for determining the circumferential position of each disk on the drum, and means for securing the disks in position axially of the drum.

15. A pattern mechanism for dictating changes in the parts of a knitting machine 120 comprising a drum provided with a keyway and with a flange at one end, a series of split cam disks each having a projection engaging the keyway, spacing disks between the cam disks, and a nut for clamping the assembled disks against the flange on the 125 drum.

MAX C. MILLER.
